MACHINE FOR INTERPRETING AND PRINTING PERFORATED RECORDS

Clair D. Lake, Binghamton, and Francis E. Hamilton, Endicott, N. Y., assignors to International Business Machines Corporation, New York, N. Y., a corporation of New York

Application October 18, 1938, Serial No. 235,610

8 Claims. (Cl. 101—93)

This invention relates to tabulating machines and more particularly to machines of the type capable of sensing perforated records, interpreting the meaning of the perforations and controlling the operation of the printing mechanism to print the amounts represented by the perforations on the records.

Machines of the above type have been utilized for printing on perforated records to form checks issued for payment of some monetary transaction and machines of the above type have been found to be highly accurate in their operations when used commercially. Nevertheless, any single instance of improper printing should be guarded against however rare its occurrence. Such improper operations may result from wear of parts, dust, change in adjustment of parts, the probability of an unpunched or off-punched hole in the card, omission of a hole in a column, a broken plug wire, etc., and the signaling to the user of such a change or condition is an indication of requirement of service for such machines to prevent repetition of improper printing. It is, therefore, the main object of the present invention to provide a machine for printing under control of a perforated record an amount represented by the perforations of the record and to provide comparing mechanism for indicating to the operator when the amounts have not been accurately printed.

More specifically, it is an object of the present invention; to analyze a record to cause under control of the analyzing means the setting of a single set of type bars to print an amount, preferably on the perforated record; to provide means controlled by the single set of type bars and the analyzing means to determine whether the type bars have been accurately set to print the amount represented by the perforated record; and to prevent the printing operation when a type bar has not been accurately positioned.

As is well known machines of the above class are controlled by records which are perforated in columns and the perforation placed in the column is indicative of the particular digit represented in that column and may be either the digits 0 to 9 inclusive and two special perforations representing the numerals 11 and 12. The present machine is provided with a mechanism, preferably electrically controlled, which determines whether the type bar has been properly positioned to represent any of the digits 0 to 9 in each of the columns from which printing is effected.

In some systems it is the practice to com-

pletely perforate a field of the card to represent all of the digits 0 to 9. Specifically where a four column field is perforated with a number having two denominational digits, the remaining two columns at the left would be perforated to represent "0." This provides a convenient checking system to ensure against omissions.

It will be obvious that in the printing of a two digit number, such as, for example, -24- the two columns at the left would be represented on the card by perforations indicating -0024. The present machine would print this amount as -0024- and obviously the printing of the unnecessary zeros might bring about confusion in reading the amount and would be altogether undesirable when printed upon a tabulating card which is to be used as a check. These two columns must be printed blank or if so desired printed with an asterisk. Again considering the four digit number -0204 the suppression of the printing of the unnecessary zeros at the left will, in the present machine, prevent the printing of the "0" between the two digits "2" and "4" and other means are herein provided for causing the zero insertion by mechanical means and hereinafter is designated as "mechanical zero." With an understanding of the above, it is explained that the present machine is provided with a means for determining whether the type bar has been properly positioned to print the mechanical zero, or if the type bar has been set to a blank or asterisk printing position, and the determination of the accuracy of such positioning of the type bar is also a further and important object of the present invention.

The machine is provided with a means for determining the above and is preferably electrical in control and operation and together with the other checking means previously described for the digits 1 to 9 is capable of determining whether the type bar has been accurately positioned for all of the type carried thereby and from which printing operations can be effected.

As is well known, the perforated card is disposed and passed through the machine so that the digits are analyzed in the sequence 0, 1, 2, 3, 4, 5, 6, 7, 8 and 9 and the machine first analyzes and determines whether any of the aforesaid digits are represented in a column of the card and the comparing or checking means is controlled by the analyzing means and the position of the type bar so as to determine the proper positioning of the type bar in accordance with the aforesaid digits to be printed. In the event

that none of these digits are to be printed but

under the conditions previously mentioned a mechanical zero is to be printed, or an asterisk or the type bar positioned to the blank printing position, the machine is capable of sensing this fact and automatically brings into operation a checking mechanism to check the position of the type bar for its setting at the blank position or printing at the mechanical zero or asterisk printing position.

It is a further object of the present invention to cause the aforesaid checking and comparing mechanisms to control the operation of the machine and more specifically it is an object of the present invention to cause the machine to be stopped whenever it is determined that improper printing will result from any of the aforementioned causes. The machine is preferably so constructed that the machine will stop before the type hammers will be released to cause the improper printing of the result.

By constructing the machine in the above described manner it will not be possible to improperly print amounts, and the operator will be signaled whenever such improper printing is liable to occur. Hence the machine will operate in a more efficient manner than heretofore, and more perfect operations thereof will ensue.

Further objects of the instant invention reside in any novel feature of construction or operation or novel combination of parts present in the embodiment of the invention described and shown in the accompanying drawings whether within or without the scope of the appended claims and irrespective of other specific statements as to the scope of the invention contained herein.

Card feeding mechanism

In more detail, 10 (Fig. 2) represents the main drive shaft of the machine. This may be driven

in any suitable manner as by an electric motor through belt 11 rotating a pulley attached to a shaft 15. A uni-directional coupling 12 is interconnected between shaft 10 and 15.

From shaft 10 a worm 13 (Fig. 2) drives worm wheel 14 secured to a shaft 15 to which is also secured a box cam 16. A pivoted cam follower arm 17 has a roller 18 at one end riding in the cam groove and at the other has connection to an arm 19 through adjustable rod 20.

Arm 19 is secured to a shaft 21 having arms 22 (see Fig. 1) in pin and slot engagement with pickers 23 mounted for reciprocation in the frame of the machine. This reciprocating picker mechanism is adapted to advance one record card at a time from the supply stack or magazine 24.

Shaft 15 through gears 25 shown in Fig. 2 drives a parallel shaft 26 which has threaded sections 27 meshing with worm gears 28 on feed roller shafts 29 to drive feed rollers 30 (Fig. 1) constantly. The card which is advanced by the picker passes into the bite of the first pair of feed rollers 30 to the left in Fig. 1 and is subsequently guided to the analyzing or perforation reading devices which comprise brushes 31 and a contact roller 32. These brushes and contact roller are of conventional structure such as is commonly used in electrically controlled tabulating machines.

After passing the analyzing brushes 31 the cards pass to the second pair of feed rollers 30 which advance each card to a pair of intermittently driven rollers comprising upper spring pressed rollers 33 and lower rollers 34 which engages the edge of the card. These rollers 33 and 34 advance the card to printing position at which time they momentarily pause in their rotation to stop the feeding of the card to permit printing on the card in accordance with the preceding analysis.

This interruption in the advance of the card is accomplished as follows: Rollers 34 are secured to a shaft 35 (Fig. 1) journaled in the frame of the machine and having attached at one end a gear 36 (Fig. 2) meshing with a gear 37 on shaft 38 on which shaft is also a gear 39 adapted to be driven by a mutilated gear 40 free on the continually running shaft 15. Gear 40 carries a pin 40a (see Fig. 3) which may be set in any one of five slots 40b in a disk 40c which is integral with worm wheel 14. Gear 40 is supported by a sleeve 40d which is loosely mounted on the shaft 15.

During the rotation of shaft 15 the gear 40 will pick up gear 39 by means of pin 40a to advance the card to printing position, upon reaching which, the toothless portion of gear 40 moves into locking engagement with gear 39 as shown in Fig. 3. After printing has been effected gear 39 is again engaged for rotation and the card is fed forward to a conveying means (Fig. 1) comprising rollers 41 and tracks 42 which convey the card to a suitable stacker 43 where they are collected. The shafts upon which rollers 41 are secured are adapted to be continually driven by reason of the gear connections 44 to the shaft 26 as shown in Fig. 2. It is the frictional engagement of rollers 41 with the upper surface of the card which causes the card to be advanced along the tracks 42.

It will be apparent that by altering the relationship between gear 40 and wheel 14, the position on the card in which printing is effected will be altered, that is, if the cam portion of gear 40 is earlier retarded in its time of opera-

tion, the card will be interrupted sooner and a lower line will receive the printing impression.

Printing mechanism

For effecting the printing on the record cards as they successively pass through the machine a plurality of type bars 45 (Fig. 1) are provided. These bars are all mounted for reciprocation in the frame of the machine and each has a connection through a spring-pressed pawl 46 to 10 a crosshead 47. Thus, in Fig. 1, upon movement of crosshead 47 to the left the pawls 46 through frictional engagement with bars 45 will move the bars concurrently in the same direction.

The bars may be arrested at any point in their travel and subsequently the pawls 46 will disengage and permit the further movement of the crosshead 47. Upon the reverse movement of crosshead 47 the shoulders 185 (Fig. 6) of the bars 45 will be engaged thereby to positively move the bars to restored position. For reciprocating the crosshead 47 the following mechanism is provided.

As shown in Fig. 2 the crosshead 47 is connected at its ends to blocks 48 slidable upon rods 49 and having pivoted link connections 50 to a follower arm 51 pivoted at 52. Arm 51 has a roller 53 cooperating with the cam groove of a box cam 54 mounted on a shaft 55 connected through worm gear 56 and worm 57 to the constantly running shaft 10. The arrangement and timing of the parts is such that the type bars 45 are advanced under the influence of pawls 46 synchronously with the movement of a card past the analyzing or sensing brushes 31.

If a perforation at, say, the "5" position on the card is under the sensing brushes, the corresponding type representing "5" will be at the printing line. The establishment of an electric circuit through the index point perforations by the brushes is adapted to energize a magnet 58 (Fig. 1).

There are a number of these magnets 58, each magnet being related to a corresponding type bar 45. The energization of any magnet is adapted to release a pawl device 59 through a wire 61 and latch 62 and allow it to engage one of the ratchet teeth 60 on the bar 45. After pawl 59 has engaged the teeth 60 further movement of the type bar 45 to the left in Fig. 1 is prevented. The type bars 45 are positioned during a passage of a card past the brushes. Subsequently these type bars are held during the period that a card passes from the analyzing station to printing position and during the printing operation. After the printing operation, pawls 59 and latches 62 are positively restored in the following manner.

Secured to shaft 55 is a cam 63 (Fig. 1) against which presses the roller of an arm 64 and which latter is pressed upwardly by a spring 65 acting through an arm 66 on shaft 67. The shaft 67 has secured thereto arms 68 which carry a restoring plate 69. Arms 70 pivoted to arms 68 carry a restoring plate 71. By this construction cam 63 is adapted to move plate 69 to the left to restore pawls 59 and plate 71 is moved upwardly to restore latches 62 and their connected wires 61.

For each type bar 45 there is an individual hammer 72 which is adapted to strike the particular type 73 on the type bar which is at the printing line. The hammers are pivotally mounted on a rod 74 carried by a bar 75 and depend for their actuation upon movement of said bar. The bar 75 is pivoted on the frame of the 75

machine by pintles coaxial with rod 74 and has springs 76 biasing the bar in a clockwise direction in Fig. 1.

To the middle of bar 75 there is pivoted a cam 5 follower arm 77 bifurcated to straddle shaft 55 and having a roller 77a in cooperation with a cam 78. Fixed to one face of the cam 78 is a cam member 79 which cooperates with a projection 80 of the cam follower arm 77.

As the cam 78 revolves, by virtue of the shaft 55 being driven in the manner previously described, it cooperates with the arm 77 through its follower roller 77a, gradually retracting the hammers 72 in a counterclockwise direction against the tension of springs 76.

As the roller 77a leaves the high point of the cam 78, member 79 engages the projection 80 and upon continued rotation of the cam the projection 80 drops from the member 79 and the springs 76, thus released, turn the common bar 75 in a clockwise direction to swing the hammers 72 against type 73 thus effecting printing.

Referring to Fig. 1, 81 designates a printing platen journaled in the frame of the machine and adapted to be rotated by frictional engagement with the passing card to prevent excessive wear at any one place. The inking ribbon devices are of conventional form and require no detailed description the ribbon 82 being guided along the platen 81 and beneath the tabulating card.

Circuit diagram (Fig. 15)

In machines of this type, it is desirable that the circuits which are closed through the perforations in the card to the magnets 58 be interrupted before the brushes 31 leave the perforations in order to prevent arcing at the brushes. To this end, circuit breaker contacts 88 are provided as shown in Fig. 15.

The circuit breaker contacts CB-88 are adapted to be closed by a dentated cam 89 which is driven by the shaft 55 (Fig. 2) so as to rotate once for each operation of the machine. The contacts 88 are operated by the teeth of the dentated cam 89 so as to make contact and hold such contact until the perforation has left the brush 31. The circuit to the magnet 58 through the hole in the card is described as follows for one card column; from the line side 91, through 45 card lever contacts CL closed when cards are being fed, wire 93, circuit breaker contacts 88, common contact roller 32, a brush 31, a plug connection 95, magnet 58, a switch 98, wire 99 and a wire 100 to the other line side 101.

55 A set of switches 102, as more particularly explained in Patent No. 1,946,900, is provided and when one of the switches 98 is open and one of the switches 102 for the same column is closed the above described sensing circuit is conducted 60 from magnet 58 through a switch 102, wire 103, cam contacts CC-6 to the line side 101. Cam contacts CC-1 and other CC contacts to be hereinafter referred to are controlled by cams on the shaft 55 and from the timing diagram in Fig. 14, it will be seen that the cam contacts CC-6 are timed to be open during the time the "12th," "11th," and "10th" or "0" index points on the card arrive at the sensing brushes 31 and to close after the "0" index point position has passed the brushes 31 so that the occurrence of a perforation in the "10 or 0," "11th" or "12th" positions would not be effective to cause the energization of the magnet 58 in the columns in which switches 98 are open and switches 102 closed.

Referring to the wiring diagram (Fig. 15) cer-

tain of the mechanical parts are shown in diagrammatic form in this figure. In this figure M designates the electrical motor which by the belt and pulley connection previously referred to drives the main drive shaft 10 of the machine. This shaft through the gearing described drives the picker devices which rotate the fed rollers to advance and feed the card past the analyzing brushes 31 and in passing the brushes the usual card lever is pressed by the cards thus closing card lever contacts CL.

To start the machine in operation, the operator first closes the main line switch 121 and thereafter the "Start Key" is depressed to close the start key contacts 122 which upon closure establish a circuit from the line side 91 through these contacts to a motor relay magnet 124, to motor M, and to the line side 101. The energization of the motor M causes the feeding of the cards so that the card lever CL closes its contacts to cause the energization of a card lever relay magnet 125 by shunting it across the line sides 91 and 101. This closes the relay contacts 125a which together with the relay contacts 124a establishes a holding circuit for the motor M from the line side 91 through stop key contacts 128, relay contacts 125a, cam contacts CC-5 now closed, relay contacts 124a, motor relay magnet 124, motor M through line side 101.

A cam contact CC-2 is provided to hold this circuit during the interval between cards when relay contacts 125a will be open and the circuit is described as follows: From line side 91, cam contacts CC-2, cam contacts CC-5, relay contacts 124a, motor relay magnet 124, motor M to the line side 101. Contacts CC-2 also serve to take the arc from the relay contacts 125a with which it is in parallel.

Printing of zeros is effected by the usual zero insertion devices, the description of which will now be given for a clearer understanding of the present invention, but for further details of description and operation, reference may be had to the patent to G. F. Daly, No. 1,946,900 issued February 13, 1934.

Referring to Fig. 8, it will be noted that the "0" index point position of the card is also used in certain cases to represent the number "10," as when a date is recorded, also that the "11th" and "12th" index point positions are adapted to 50 control the position of the type bar so as to print "11" and "12," respectively. The type elements 73 in Fig. 7 are arranged to successively present themselves in printing position in the order indicated, synchronously with the passage 55 of the corresponding index points on the card past the analyzing brushes. It is quite obvious that if perforations in the "0," "11th" or "12th" index point positions were permitted to control the magnet 58 the corresponding numerals would be printed. Hence, in columns other than those in which "10," "11" or "12" is represented, the switches 98 will be moved to open position and the switches 102 in closed position and the magnets 58 associated therewith will not interrupt their respective type bars to select the "10," "11" or "12" type for printing. Such type bars unless otherwise interrupted in their advance, as will hereinafter be set forth, will present a dummy element 73a in printing position. This element 70 73a has the usual type element spring structure of the type elements 73 and when struck by the hammer will not permit any printing on the record card.

Printing of zeros will be effected under control 75

of a significant figure in a predetermined column as follows:

Zero printing

In Figs. 1, 11 and 12 a series of members 110, one for each type bar, is pivoted on a rod 111 and each is held in either the position shown in Fig. 11 or Fig. 12 by a spring pressed latching bar 112. Cooperating with the members 110 is an index strip 113 (Figs. 11 and 12) designating the columns to which the members 110 are related. The bar 112 is provided with side arms 119 to permit individual manual adjustment of members 110 and for retaining them in their adjusted positions.

Each member 110 is provided with a spring urged lever 114 pivoted thereon at 115. When a member 110 is adjusted to the Fig. 12 position, the free end of the related lever 114 will enter a notch or slot 117 in the related type bar 45 if the type bar is not stopped at the digit positions 1-9 when the type bar reaches its extreme leftward movement, as shown in Fig. 12, causing such type bar to be stopped to a position where the dummy element 73a, of Fig. 7 is presented to the printing position.

If a member 110 is adjusted to the position shown in Fig. 11 and the type bar 45 is not adjusted to a digit position 1-9 the type bar 45 will also be stopped to a position where the dummy element 73a, of Fig. 7 is presented to printing position.

Each lever 114 has a laterally extending arm 116 projecting under the lever 114 of the next high denominational order, as shown in Fig. 13. If a member 110 is in the Fig. 11 or Fig. 12 position its lever 114 will engage the arm 116 of the lever 114 of next lower order to retain this lever depressed so that it will not pass into the recess 117 and its free end will be positioned in the path of a stop 118 of the type bar 45 and the type bar 45 will be permitted to move to a point where the zero type element is presented to the printing position. As will be made clearer later on, if a member 110 is in the Fig. 11 or Fig. 12 position the related lever 114 will only effect the above operation if the related type bar is moved to select the type 1-9, thus causing the insertion of necessary zeros, or printing the so-called "mechanical zero."

With all the members 110 in the position shown in Fig. 12 zeros are adapted to be printed across the machine to the left of any significant figure. The rocking of any member 110 to the Fig. 11 position will interrupt the carrying across of zeros at such point. The functioning of the various parts may best be explained in connection with a specific example.

For instance, for the card shown in Fig. 8 for all columns except the one containing the month designation of the date, the corresponding switches 98 in Fig. 15 will be in open position and the switches 102 in closed position. This, as has already been seen, will permit the reading by the analyzing brushes of perforations in the "0" index point position of such columns but prevent printing control magnets 58 from being energized. Considering now the field of the card headed "Amount" the member 110 associated with the first undesignated column to the left of this field and the first column following the field to the right, namely, the "Mo." column will be moved to the position of Fig. 11 the setting of these two members being shown in Fig. 13. This adjustment will prevent the carrying of zeros into the "Amount" field from the right and will interrupt

passage of zeros to the undesignated field adjoining it on the left. Fig. 10 shows a relation of levers 114 of the second column of the field wherein the undesignated field and the first column of the "Amount" field wherein the lever for the last mentioned column has been moved to the left without moving out of controlling engagement with the arm 116 of the next lower denominational order, so that if the related lever 114 is held depressed by reason of its associated type bar being stopped at a significant digit or "4" position, all the levers 116 to the right will be held depressed to the extent of the field. This will cause such type bars, if they are not set to print the digits 1-9, to print a zero, thus causing the zero insertion.

In Fig. 9, the lever 114 of the first column of the next or "Mo." field will be to the left as shown and its arm 116 will lie under a notch 120 in the lever 114 next higher in order. This relation of the parts, as is readily understood, prevents the depression of lever 114 at the left from influencing the lever 114 on its right. In an identical manner, the last column at the left of the "Amount" field in Fig. 8 is prevented from exerting an influence over columns in the next undesignated field.

By way of further illustration, consider a single entry in the units column of the "Amount" field and zeros punched in the three remaining columns. These three zeros have been analyzed by the brushes but their printing control magnets 58 are not energized so that the associated type bars will be moved to present the dummy elements 13a to printing position, and only the units column will stop its type bar to print from the particular type selected.

Checking for determination of correct position of type bars

It is desirable to check the position of the type bars to ascertain whether the proper positioning is effected in accordance with the perforations of the record card. This is performed by mechanism shown particularly in Figs. 4, 5, and 6 and explained in connection with the wiring diagram. For each type bar there is provided a camming lever 158 pivoted at 159 to the cross head 47 and provided with a high portion 162 cooperating with a tail 160 (Fig. 4) of the pawl 46 when the cross head 47 is moved slightly to the left as will be made clearer later. The camming lever 158 is also provided with a recess 161 to the left of the high portion 162.

When the pawl 62 is unlatched (as shown in Fig. 6) due to the energization of magnet 58, after a short interval of the movement of type bar 45 the pawl 59 will engage the notch 60 to stop the type bar 45 and as the cross head 47 continues further after the type bar is stopped, a cam edge 163 of the stopped type bar 45 will rock the pawl 46 so that the tail 160 in engagement with the portion 162 of lever 158 will rock the lever 158 so that it actuates a T-shaped lever 164, the latter being carried by a pair of arms 165 loosely mounted on rods 166. A continued rocking of the pawl 46 will cause the tail 161 thereof to slip by the high portion 162 and into the recess 161 permitting both the lever 158 and the T-shaped lever 165 to be rocked upwardly to 70 normal by their springs.

For one denominational order of the type bars 45 the upper arm 165 has integral therewith an arm 167 adapted to close a pair of contacts 168a. Each of the type bars will cause the closure of a 75

related pair of contacts 168a. For the next denominationally ordered type bar it will be seen from Fig. 5 that the lower arm 165 has an integral arm 169 adapted to close its pair of contacts 168a. This construction is desirable in order to provide for the proper side spacing of the pairs of contacts 168a since each is substantially wider than a type bar 45. The above arrangement is repeated for the next two adjacent orders of the set of type bars as best shown in Fig. 5.

The type bars are restored at the end of the cycle as previously stated by causing the cross bar 47 to contact with the shoulders 185 of the type bars 45 restoring the latter to their home positions as shown in Fig. 1. As the cross head returns to home position, a plate 186 (Fig. 4) contacts with the extremities of the levers 158 causing them to be rocked to disengage the tail 160 from the recess 161 to cause the parts to have the relation shown in Fig. 1. At the initial operation of the machine, the cross head 47 carries the lever 158 out of engagement with the cam plate 186 permitting the lever 158 to be rocked by its spring so that the tail 160 occupies a position on top of the portion 162 of the lever 158 as shown in Fig. 4, the parts now being in position to cause the closure of a related pair of contacts 168a by the stoppage of the type bar as previously explained.

It is explained that the type bar 45 is stopped to select the mechanical zero, and is also stopped to select the dummy printing element, as before explained, and in each of such instances the contacts 168a will also be closed in the manner just explained. The stopping of the type bar 45 is, in these type selecting operations, effected under control of the levers 114, rather than by the pawl 59.

40 Checking position of type bar for printing digits 1, 3, 5, 7, and 9

There will now be described the means for determining whether the type bar is positioned to print the digits 1, 3, 5, 7 and 9, in accordance with the perforations of the card, and in connection with the wiring diagram of Fig. 15 and the timing diagram of Fig. 14.

When the circuit breaker 88 transmits an impulse to the printing magnet 58 for the digits 1, 3, 5, 7 and 9, for selection of "odd type," a circuit closer C-130 will close at such time intervals and this circuit closer is preferably in the form of a commutator, as shown diagrammatically in Fig. 15, and it is rotated by a shaft driven by the drive shaft 10. At such time intervals an impulse will be transmitted to a relay magnet by a circuit described as follows: from the plug socket of column 1, for example in which plug 95 is inserted, a wire to a pick up relay magnet 131, through the commutator C-130 to the line side 101. Hence relay magnet 131 will be energized simultaneously with the printing magnet 58. Relay magnet 131 will close its relay contacts 131a thus complete a circuit to holding magnet 133, the circuit to energize the holding magnet 133 being closed by a circuit breaker CB-131 which is timed to close at the odd or 1, 3, 5, 7 and 9 time intervals and the cam of which is rotated by a shaft driven by shaft 10. The holding relay magnet 133 when energized will close a series of relay contacts 133b, 133c and 133d, and the circuit breaker CB-131 is timed to keep the circuit to relay magnet 133 closed for 1½ index points and thus holds the energization of the

magnet 133 for this period of time, for a purpose now to be explained.

From Fig. 15 it will be seen that a relay magnet R-3 is in circuit connection with a type bar contact 168a, the relay contacts 133b, and circuit breaker contacts CB-139 which are driven in a manner similar to contacts CB-137. While the magnet 58 stops the type bar an appreciable time is required to close the checking contacts 168a and from Fig. 14 it will be seen that this occurs about a point after the perforation is analyzed, hence it is necessary to cause the contacts CB-137 to be timed to retain magnet 133 energized and relay contacts 133b closed to this next index point, as will be seen from Fig. 14. The circuit breaker contacts CB-139 are timed to close when the contacts 168a close for odd type selected and hence if the type bar is properly positioned the relay magnet R-3 will be energized and the latter will close its relay contacts R-3a, and R-3b a stick circuit will be maintained for this relay R-3 through the relay contacts R-3a and cam contacts CC-3.

When relay contacts 133c close a circuit will be closed to a relay magnet R-5 through the cam contacts CC-3. Relay magnet R-5 will close its relay contacts R-5b, and stick contacts R-5a. From Fig. 14 it will be seen that cam contacts CC-3 close for a considerable period of the operating cycle to thus maintain relay magnets R-3 and R-5 energized through their respective relay contacts R-3a and R-5a respectively.

Assuming for clarity that only a single column is to be checked for accuracy in printing it will be seen that a checking circuit is made from the line side 91, a wire 141, a plug connection 143, relay contacts R-5b, relay contacts R-3b, relay magnet 135, to the line side 101, thus energizing relay magnet 135 as long as cam contacts CC-3 are closed. From Fig. 14 it will be seen that when cam contacts CC-5 open, cam contacts CC-3 are closed and if the proper type is selected of digits 1, 3, 5, 7 and 9 relay contacts 135a will be closed when cam contacts CC-5 open, and hence the circuit to motor relay 124 will not be interrupted and another cycle of operation will ensue.

Checking type bar for printing 10 or 0, 2, 4, 6, 8

Substantially the same arrangement is provided to check the printing of either digits 10 or 0, 2, 4, 6, or 8 and in this instance for one column, a relay magnet 132 is energized through a commutator C-140 closing at the even index point positions, and is driven like the commutator C-130. The relay magnet 132 is energized to close its relay contacts 132a to cause a holding magnet 134 to be energized, the circuit being closed through the circuit breaker CB-142 closing at the even index points and driven like contacts CB-137. The holding magnet 134 closes its relay contacts 134b, 134c, and 134d. The relay contacts 134b close a circuit to relay magnet R-3, if the type bar contacts 168a close at the time relay contacts 134b close effected when the type bar is properly stopped, the circuit being through circuit breaker contacts CB-144 which are also driven like contacts CB-137. The closure of relay contacts 134c will cause the energization of relay magnet R-5 through cam contacts AC-3. The time relationship of the contact closing time of commutator C-140, circuit breaker contacts CB-142, and CB-144 is the same as explained for commutator C-130, circuit breaker contacts CB-137 and CB-139. 75

Hence upon proper position of the type bar for even digits relay magnets R-3 and R-5 will both be energized to cause the continued operation of the machine.

5 Checking of type bar position for mechanical zero insertion or blank position

It has previously been explained that under certain conditions a type bar may advance to 10 present a dummy type 13a in printing position and under certain conditions it may not be desirable to print the zeros at the left of the highest significant digit and to insert the zeros for necessary orders by the so-called "mechanical zero" devices disclosed in Figs. 9-13. For example in 15 representing the number -203- on the card for four columns it would be represented -0203- on the card and the switches 102 for the four left digit positions or -020- would be opened and corresponding switches 98 closed. This is desirable 20 as a number -0003- may also appear. For the number -0203- the first column from the left -0- will go to blank position. For the third column from the left -0- the zero will be inserted by the 25 mechanical zeros and while "0" is perforated on the card it will be analyzed but it will not cause the energization of the printer control magnet 58, but relay magnet 132 will be energized. The machine is provided also with means to detect 30 whether the type bars are at the blank or mechanical zero and is described as follows:

From Fig. 15 it will be seen that a relay R-7 is in series with relay contacts 133d, or relay contacts 134d and cam contacts CC-1 and the latter are timed to close the circuit to relay R-7 whenever relay contacts 133d or relay contacts 134d close due to the analysis of a perforation at the index point positions 1-9 inclusive, either even or odd, but not including the "0" perforation.

40 Relay magnet R-7 will close its stick contacts R-7a to hold the energization of relay magnet R-3 through cam contacts CC-3.

In the event that there is no perforation 45 analyzed at the 1-9 index point positions relay magnet R-7 will not be energized and thus relay contacts R-7b will remain closed and a circuit will be made from the line side 91, through cam contacts CC-4, relay contacts R-7b, type bar contacts 168a, relay magnet R-3 to the line side 101.

50 From Fig. 14 it will be seen that the type bar contacts 168a also close for the mechanical zero, or blank positions and which may be an asterisk -*-, and such closure is indicated as the last two 55 intervals of closure. After the type bar is stopped for printing from either the mechanical zero or the asterisk type, contacts 168a close and, as previously explained, these contacts close about one point later in the cycle, and at this time it will be seen that cam contacts CC-4 close so as to energize relay magnet R-3 which closes its stick contacts R-3a and its checking contacts R-3b.

60 It will be noted that when there is a zero perforation relay magnet 134 will be energized to close its relay contacts 134c, to cause, by the circuit previously described the energization of the relay magnet R-5. The latter will close its relay contacts R-5b, and together with the relay contacts R-3b will cause, upon proper type bar positioning, the energization of the relay magnet 135.

65 When it is desirable to print zeros under control of the zero representing perforations the switches 98 for these columns are closed and the switches 102 for these columns are opened. This

will cause the selection of the first "0" type on the type bar 45, and which in Fig. 7 would replace the "10" type. The comparing operation is the same as previously described for checking of the printing of the digits 10 or 0, 2, 4, 6 and 8. Of course in such printing of zeros the mechanical zero printing is not effected and all the zeros in a number will be printed under control of the zero perforations in the card columns representing the number.

Machine control in accordance with checking operations

The above described arrangement has been described for a single order but the circuit diagram discloses the circuit arrangement for two orders, but the operation is identical. For the second column the checking circuit comprises relays R-4, R-6, and R-8 corresponding to relays R-3, R-5, and R-7 in functions and operation. When two columns are used for checking the right end of the plug connection 143 will be inserted in a socket 144, so that the contacts of relay magnet R-6 and R-4 control the energization of the relay magnet 135.

In the event that the circuit to magnet 135 will be opened due to the opening of one of the relay contacts in the circuit then relay contacts 135a will be open when cam contacts CC-5 open and thus the stick circuit to motor relay magnet 134, and motor M will be opened and the motor will stop. Cam contact CC-5 is timed to stop the machine before the time the printing hammers are released. The hammers are adapted to be released for striking the selected type 13 at the time in the cycle substantially at the time disclosed in Fig. 14, this occurring after all the type bars have been set. In practice it has been found that the energization of the relay magnet 135 will cause the stoppage of the motor M prior to the time that the hammers are released to prevent improper printing upon the perforated card.

The indication, given by the stoppage of the machine with cards in the magazine 24, informs the operator that an improper printing operation has been prevented. With the machine stopped after partially completing its cycle of operation, the operator inserts a rod 183 (Fig. 1) in the machine frames to block the hammers 72 and prevent them from striking the type 13. The machine is provided with a hand wheel 184 (Fig. 8) and by manually turning this the shafts 157 and 10 (Fig. 2) are turned so as to complete the cycle of machine operation to feed the card past the hammers 72. When the card has reached such a position the rod 183 can be removed and the machine restarted so as to complete printing operations on the remaining cards. The unprinted card can, of course, be located in the storage hopper or if the operator watches carefully it can be received by hand as it is fed by the last set of rollers 41.

Attention is directed to the fact that cam contacts CC-3 will hold the relays R-3, R-5 or R-4 and R-6 energized even though the machine stops and thereafter. This will permit a visual inspection of the condition of the relays and reference thereto will indicate which relay has not energized, and, therefore, the column failing to check.

While there has been shown and described and pointed out the fundamental novel features of the invention as applied to a single modification, it will be understood that various omissions and substitutions and changes in the form and de-

tails of the device illustrated and in its operation may be made by those skilled in the art without departing from the spirit of the invention. It is the intention therefore to be limited only as indicated by the scope of the following claims.

What is claimed is:

1. In a checking device for a printing apparatus, a plurality of type elements each having a certain printing position and other digit representing positions, control means, means for setting said type elements to said digit representing positions under control of said control means, or to said certain printing position, means cooperatively related with said type elements to check the positioning of said type elements at said other printing position, and means for causing said last named means to be operative and effective upon the determination that said type elements are not set at said digit representing positions.
2. In a checking device for a printing apparatus, a plurality of type elements having digit representing printing positions and other printing positions, control means, means for setting said type elements to said digit representing positions under control of said control means or alternatively, to either one of said other printing positions, means cooperatively related with said type elements to check the positioning of said type elements at either of said other printing positions, and means for causing said last named means to be operative and effective upon the determination that said type elements are not set at either of said other printing positions.
3. In a checking device for a printing apparatus, a plurality of type elements, each having digit representing positions and a zero printing position, control means for determining the digit representing positions of said elements, means for setting said type elements to said digit representing positions under control of said control means, or to said zero printing position, checking means comprising means controlled by a type element to be positioned to zero printing position for determining whether said element is properly positioned at said zero printing position, and means for causing said checking means to be operative and effective upon the determination that said type elements are not set at said digit representing positions.
4. In a checking device for a printing apparatus, a plurality of type elements each of which is settable to digit positions 1-9 or 0, means for controlling and effecting the setting of certain of said elements to said digit positions 1-9, the other of said type elements being set to the 0 printing position, comparing means comprising means under control of the type elements for determining whether the latter are positioned at the digit positions 0, and means for rendering said comparing means effective and operative upon the determination that said type elements are not set at said digit positions 1-9.
5. In a checking device for a printing apparatus, a series of members of different denominational order, each member carrying a plurality of type settable to type printing positions 1-9 or 0, means for analyzing a plurality of columns of a perforated card, means controlled by said analyzing means for positioning said members to print the digit positions 1-9, certain of said members which are not set to digit positions 1-9 being positioned to said 0 position for zero insertion, electrical checking means operative upon setting of a member to said 0 position

for determining whether the member has actually been positioned to the 0 position for zero insertion, and means for causing said electrical checking means to be operative and effective upon the determination that said type members are not set at said digit positions 1-9.

6. In a checking device for a printing apparatus, a plurality of type carrying members positionable to select the type 1-9 or a mechanical zero type, means for causing a type carrying member to be positioned to select the mechanical zero type for zero insertion when said member is not positioned to select type 1-9, testing means comprising means controlled by a type carrying member to be positioned for the selection of the mechanical zero type and responsive to its proper positioning for the selection of such type for determining whether said type carrying member has actually been positioned for the selection of the mechanical zero type, and means for causing said testing means to be operative and effective upon the determination that said type elements are not set at positions to select the type 1-9.

7. In a checking device for a printing apparatus, a plurality of type carrying members each positionable to select the type 1-9 or a mechanical zero type, control means, type bar positioning means for causing the position of a type carrying member under control of said control means to select said type 1-9 when said type bar is not positioned to select the zero type for zero insertion, means for testing whether said type carrying members are positioned to select the

type 1-9 and including devices operated in response to the positioning of a type carrying member for the selection of the type 1-9 and also for the mechanical zero type, other testing means controlled by said devices when the latter is to be operated in response to the positioning of a type carrying member for the selection of the mechanical zero type for determining whether the last named type carrying member in the absence of a setting to select type 1-9 has been actually positioned for selection of said zero type, and means for causing said last named testing means to be operative and effective upon the determination that said type carrying members are not set to positions to select the type 1-9.

8. In a checking device for a printing apparatus, a plurality of movable type elements having digit positions 1-9 and 0, mechanical zero positioning means for stopping one of said type elements at said 0 printing position when said type element is not set to any digit position 1 to 9, means for controlling the setting of said plurality of type elements to digit positions 1-9, checking means comprising means controlled by the type element which is to be positioned to the 0 printing position for determining whether said last named type element is actually set to said 0 printing position, and means for causing said checking means to be operative and effective upon the determination that said type elements are not set to any of the digit positions 1-9.
